UNITED STATES PATENT OFFICE.

HENRI DELPORTE, OF OUGREE, BELGIUM, ASSIGNOR TO SOCIÉTÉ ANONYME OUGRÉE-MARIHAYE, OF OUGREE, BELGIUM.

SKIP.

Application filed June 18, 1921. Serial No. 478,669.

To all whom it may concern:

Be it known that I, HENRI DELPORTE, a subject of the King of Belgium, residing at 15 Rue de la Station, Ougree, Liege, Belgium, have invented certain new and useful Improvements in or Relating to Skips; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 This invention relates to a skip for raising ores or coal and relates specifically to the type which are pivotally mounted on a frame slideable between vertical guides and tipped at the points of charging and discharging by means of rollers mounted on the skip which engage rails which are curved at said points.

20 In the known installations of this kind, the skip is prevented from swinging when travelling between the charging and discharging points by rollers mounted on it and travelling on suitable rails extending throughout the length of its path. At least two rails are required to prevent the swinging of the skip between the charging and discharging points, in addition to the two guide rails, thus bringing the number of rails up to four all of which extend the entire distance between the charging and discharging points.

35 This invention has for its object to make it possible to utilize only two rails along the whole length.

To that end, the rails preventing the skip from turning between the charging and the discharging points are dispensed with, and during the travel between the said points the skip is locked to the suspension frame by means of a suitable locking device which 40 is unlocked when the skip is to be tipped, the tipping being produced by means of additional rails provided only at the points where such tipping is to be effected.

45 Other characteristic features of the invention will appear from the following description of the accompanying drawings, and are specially set forth in the claims.

The drawings show by way of example a construction according to the invention and

55 relate to a tipping device installed at the framework surmounting the vertical shaft.

In the said drawings:

Figure 1 shows the skip which has reached close to the point where it is to be tipped.

Figure 2 shows the skip beginning its tipping movement.

Figure 3 shows the skip tipped.

Figures 4 and 5 relate specially to the locking device.

A skip 7 is pivoted about a pin 9 provided at the lower part of the frame 1 which is suspended from a cable 2. This frame 1 is guided throughout the whole of its travel by means of rails 3 engaged by two chocks 4 and 10 of guides provided on the said frame. It should be noted that the turning axis 9 is placed outside the vertical plane which passes through the center of gravity of the bucket in such a way that the bucket always has a tendency to move to a tilting position, this tendency being controlled by means hereinafter brought out. The tipping of the skip 7 between the charging and discharging points is prevented in the following manner: The skip has at each side a block 8 engaging with the bottom of a thickened part 11 of the frame 1, which prevents its turning backwards. On the other hand, in front, the block 8 strikes against the guide rail 3, which prevents the turning forward.

Near the point of tipping of the skip, the rail 3 is broken from *a* to *b* (Figure 5) so as to afford passage forward to the said block 8.

90 Before the block 8 reaches the broken or open part *a b* of the rail 3, the rollers 5 provided on each side of the skip 7, engage the rails 6 so that the skip will be held in the desired position as soon as the block 8 has passed through the opening in the rail 3. This movement of the block 8 is controlled by an angular movement given to the skip by the curvature of the rails 6 which guide the rollers 5. Figure 2 shows the position of the skip 7 soon after the block 8 has passed through the opening.

105 The ascent of the frame 1 continuing, the inclination of the skip will increase; at a given moment the runners 14 arranged at each side of the skip 7, will engage with rollers 15 arranged at the end of the rails 6. If the hoisting of the frame 1 continues, the

skip resting on the rollers 15 by means of its runners 14, will be raised in such a manner that its rollers 5 will engage with the curved end of the rails 13 intended to guide the skip in the event of the frame being raised too high. Soon after the rollers 5 have engaged with the rails 13, the runners 14 leave the rollers 15, and the skip is supported only by its rollers 5 travelling on the rails 13.

It is obvious that during the descent of the frame the various stages of tipping or turning follow each other in the reverse sequence, so that when the frame 1 has been lowered to a sufficient extent, the skip 7 again occupies the position shown in Figure 1.

What I claim is:

1. In a structure of the character described, a sliding frame, rails guiding sliding movement of said frame, a receptacle pivoted to said frame, one of said rails being provided with a cutout intermediate its length, guides extending from said rails adjacent the cutout, a stop for preventing dumping of the receptacle carried by said

receptacle and engaging said broken rail and movable through the cutout thereof to permit dumping of said receptacle, means carried by said receptacle for engaging said guides and moving the receptacle to a dumping position when the stop moves through the cutout of the rail, and rails extending upwardly above said guides and adapted to be engaged by the guide engaging means after the receptacle has been tilted and said means moved out of engagement with the guides.

2. The structure of claim 1 and arms extending from the receptacle for engaging the guides and forming fulcrum means permitting tilting of the receptacle to bring the guide engaging means of the receptacle into position for engaging the upwardly extending rails.

In testimony whereof I have signed my name to this specification.

HENRI DELPORTE.

Witnesses:

CHARLES MERCHIE,

ALFRED XANDER HAEGHEY.
